(57) **CLAIM**

The ornamental design for a USB charge card reader, as shown and described.

DESCRIPTION

FIG. 1 is a front perspective view of a USB charge card reader, showing a first embodiment of my new design in an open configuration;

FIG. 2 is a bottom perspective view of FIG. 1;

FIG. 3 is a front elevational view of FIG. 1;

FIG. 4 is a rear elevational view of FIG. 1;

FIG. 5 is a perspective view thereof, illustrated in a closed configuration;

FIG. 6 is a left-side elevational view of FIG. 5;

FIG. 7 is a right-side elevational view of FIG. 5;

FIG. 8 is a top plan view of FIG. 5;

FIG. 9 is a bottom plan view of FIG. 5;

FIG. 10 is a top plan view thereof, illustrated in a wide-open configuration.

FIG. 11 is a front perspective view of a second embodiment thereof, illustrated in the open configuration;

FIG. 12 is a bottom perspective view of FIG. 11;

FIG. 13 is a front elevational view of FIG. 11;

FIG. 14 is a rear elevational view of FIG. 11;

FIG. 15 is a perspective view thereof, illustrated in the closed configuration;

FIG. 16 is a left-side elevational view of FIG. 15;

FIG. 17 is a right-side elevational view of FIG. 15;

FIG. 18 is a top plan view of FIG. 15;

FIG. 19 is a bottom plan view of FIG. 15; and,

FIG. 20 is a top plan view thereof, illustrated in the wide-open configuration.
The broken lines in FIGS. 1 and 11 illustrate environmental matter that forms no part of the claimed design. The remaining broken lines in the figures depict portions of the USB charge card reader that form no part of the claimed design.
